UNITED STATES PATENT OFFICE.

JAMES GREEN, OF BRACKENRIDGE HEIGHTS, PENNSYLVANIA, ASSIGNOR TO PITTSBURGH PLATE GLASS COMPANY, A CORPORATION OF PENNSYLVANIA.

APPARATUS FOR CLEANING PLATE-GLASS-GRINDING TABLES OR CARS.

Application filed November 8, 1927. Serial No. 230,867.

The invention relates to apparatus for crushing the plaster along the edges of plate glass surfacing tables and for pushing in the pegs extending along one or both edges 5 of the tables for preventing lateral movement of the glass on the table, the invention constituting an improvement over an apparatus for performing similar functions as disclosed in the Heichert and Evans Patent 10 No. 1,610,874, dated Dec. 14, 1926. The present apparatus is designed to perform the functions of crushing the plaster and pushing the pegs with less expenditure of power and with less wear and tear upon the apparatus than is the case with the device shown 15 in said patent. Briefly stated, the desired result is accomplished in the use of rollers or wheels instead of the cam shoes 14 (Fig. 5) of the patent, two rollers being preferably 20 employed, one having a wedge shaped face to fracture the plaster and partially or entirely drive the pegs, and the other having a flat face to complete the crushing operation. The result may be accomplished by a 25 single roller having either a wedge face or a flat one, but the device works more easily and effectively if the two rollers as above specified are employed. One embodiment of the invention is illustrated in the accompanying 30 drawings, wherein:

Figure 1 is a plan view of the apparatus showing its location with respect to the edge of the surfacing table. Fig. 2 is a side elevation with a portion of the surfacing table in section. And Fig. 3 is a side elevation, 35 partially in section of one of the spring adjusting bolts and the adjusting devices carried thereby.

Referring to the drawings, 1 is the top 40 of a surfacing truck or table from which the glass has been removed and from which it is desired to remove the layer of plaster 2 extending along one edge of the table, such layer of plaster being ordinarily about 3 45 inches wide and one-quarter of an inch thick. Extending through the table top are the series of pegs 3, 3, 3, etc., such pegs when in use projecting about one-quarter of an inch above the surface of the table, and when not 50 in use being pressed down so that their upper ends are flush with the top of the table.

In order to break up this layer of plaster and push the pegs down, the wheels or rollers 4 and 5 are provided carried upon the frame- 55 work 6 beneath which the table moves in the

direction indicated by the arrow so that the wheel 4 acts as the leader, fracturing the layer of plaster and pressing down the pegs 3, 3, 3, etc., after which the roller 5 passes over the fractured material and still further 60 pulverizes and loosens it.

The framework 6 is preferably in the form of an I-beam extending transversely of the track upon which the tables are mounted and being secured rigidly in position upon the framework of the structure in which the surfacing operation is conducted. This beam 6 has bolted to its sides the brackets 7, 7 through which extend the bolts 8, 8 for adjusting the pressure exerted by the wheels 4 and 5 upon the plaster. This pressure is preferably exerted yieldingly through the springs 9, 9, which encircle the bolts 8, 8. The wheels or rolls 4 and 5 are mounted upon the axles 10, 10 carried by the four bars 70 11, 11 and 12, 12, such bars being pivoted at their inner ends to the bolt 13. This bolt 13 is supported upon a U-shaped bracket 14 secured to the web of the I-beam 6 by means of the bolts 15. The outer ends of the bars 75 11, 11 and 12, 12 are secured together by means of the bolts 16 and 17, suitable spacers 18 and 19 being provided intermediate the bars 11, 11 and 12, 12. The springs 9, 9 rest at their lower ends upon the blocks 20, 20 80 supported from the bars 11 and 12 by means of the stud bolts 21, 21 extending through such side bars and into the blocks.

Carried by the brackets 7, 7 are the swivel blocks 22, 22 having threaded trunnions at 90 their sides extending through the walls of the brackets and provided with the nuts 23, 23. Threaded upon the bolts 8, 8 and extending through the swivel blocks 22, 22, are the sleeves 24, 24 provided at their upper ends with the clamping nuts 25, 25. Surrounding the upper portions of the sleeves 24, 24 and keyed thereto are the collars 26, 26 having integral therewith the handles 27, 27. Bearing upon the upper ends of the 95 springs 9, 9 are the washers 29, 29 backed up by the nuts 30, 30, such nuts being held against rotation by the lock nuts 31, 31. By rotating the sleeves 24 from the handles 27, the bolts 8, 8 may be adjusted up and down, 100 thus adjusting the tension of the springs 9, 9 so as to secure the desired amount of pressure by the wheels 4, 5 upon the layer of plaster on the table and upon the pins 3, 3, 3, etc.

In order to reduce the amount of force required to crush the plaster, sprays of water are preferably applied to the plaster in advance of the wheel 4 and the wheels are freed 5 from any plaster which may cling thereto and interfere with their crushing action by means of the scrapers 28, 28, extending transversely of the bars 11, 11 and 12, 12 and bolted thereto.

10 In operation, the table moves beneath the pair of wheels 4 and 5 in the direction indicated by the arrow, the wheel 4 first engaging the plaster which is readily fractured by reason of its beveled face, the pegs 3, 3, 15 3 being pushed down one after the other as they are engaged by the wheel. The water supplied to soften the layer of plaster also serves to wash away this loosened material, and any plaster still left on the edge of the 20 table is further crushed and loosened when it passes beneath the flat faced wheel 5, the device thus serving to clean off the plaster and push down the pegs as the table is moved slowly from the position at which it 25 is stripped of glass to a new position of use where another sheet is supplied to the top of the table and secured in position by means of the pegs 3, 3, 3 and a suitable layer of plaster along each edge of the table.

30 What I claim is:

1. Apparatus for cleaning plaster from the edge of a moving surfacing table having a row of glass holding pegs projecting above the top of the table and through the plaster, 25 comprising a device having a roller positioned so as to engage the plaster and pegs as the table moves beneath the device and means pressing said device downwardly with sufficient force to fracture the plaster and drive the pegs downward.

40 2. Apparatus for cleaning plaster from

the edge of a moving surfacing table having a row of glass holding pegs projecting above the top of the table and through the plaster, comprising a device having a roller positioned so as to engage the plaster and pegs as the table moves beneath the device and means for pressing said device downwardly with sufficient force to fracture the plaster and drive the pegs downward, said roller 45 having its tread beveled on each side so that it is wedge shaped in cross section.

3. Apparatus for cleaning plaster from the edge of a moving surfacing table having a row of glass holding pegs projecting above 50 the top of the table and through the plaster, comprising a device having a series of rollers positioned so as to engage the plaster and pegs as the table is moved under the device and means pressing said device downwardly with sufficient force to fracture the plaster and drive the pegs downward, the first of the series of rollers having its flange or tread beveled on each side so that it is 55 wedge shaped in cross section.

4. Apparatus for cleaning plaster from the edge of a moving surfacing table having a row of glass holding pegs projecting above the top of the table and through the plaster, comprising a device having a series of 60 rollers positioned so as to engage the plaster and pegs as the table is moved under the device and means pressing said device downwardly with sufficient force to fracture the plaster and drive the pegs downward, the first of the series of rollers having its flange or tread beveled on each side so that it is 65 wedge shaped in cross section, and the next of said rollers having a flat flange or tread.

In testimony whereof, I have hereunto subscribed my name this 3rd day of Oct., 1927.

JAMES GREEN.
